SASH LOCK

Axel W. Ahlgren, Rockford, Ill., assignor to Amerock Corporation, Rockford, Ill., a corporation of Illinois

Filed Apr. 22, 1963, Ser. No. 74,547

Term of patent 14 years

(Cl. D10—11)

FIGURE 1 is a top view of the sash lock embodying my new design.

FIG. 2 is a perspective view of the sash lock.

FIG. 3 is a side elevation of the sash lock as viewed from the left in FIG. 1.

FIG. 4 is a front elevation of the sash lock.

FIG. 5 is a side elevation of the sash lock as viewed from the right in FIG. 1.

I claim:

The ornamental design for a sash lock, substantially as shown.
